UNITED STATES PATENT OFFICE.

WILLIAM C. SMITH, OF CHICAGO, ILLINOIS, ASSIGNOR TO THE PULLMAN COMPANY, OF CHICAGO, ILLINOIS, A CORPORATION OF ILLINOIS.

SCREEN FASTENING FOR CAR WINDOWS.

Application filed August 23, 1923. Serial No. 658,951.

To all whom it may concern:

Be it known that I, WILLIAM C. SMITH, a citizen of the United States, and resident of Chicago, county of Cook, and State of Illinois, have invented certain new and useful Improvements in Screen Fastenings for Car Windows, of which the following is a specification, and which are illustrated in the accompanying drawings, forming a part thereof.

This invention relates to railway cars and more particularly to the screens and screen construction for the windows of the side walls of the car.

One of the objects of the invention is the provision of a screen frame that may be easily and readily placed in position and removed therefrom without disturbing the means for supporting the same.

Other objects of the invention are the provision of a screen frame and supporting means with cooperating attaching members associated therewith that are simple in construction, efficient in operation and not likely to become broken or get out of order.

Other and further objects and advantages of the invention will appear from the following description taken in connection with the accompanying drawings, in which

Fig. 1 is a vertical section of a portion of a side wall of a passenger car showing the invention in position therein, with parts omitted and parts broken away;

Fig. 2 is a perspective view of the window supporting frame;

Fig. 3 is a perspective view of the screen frame, with the screen wire in position therein; and

Fig. 4 is a side elevation of a portion of the screen frame on an enlarged scale, with parts in section and parts broken away.

On the drawings the reference character 10 designates the side of a railway car having a window sash 11 therein. The window sash 11 is provided with one or more glass panels 12 and the lower portion of the sash is rabbeted as at 13 and again at 14 to form a stepped recess as clearly shown in Fig. 1 of the drawings. The outer downwardly extending portion 15 of the window sash formed by the stepped recess is adapted to engage the outer window sill 16 and is supported thereby when the window is in lowered position.

The sill 16 is provided with an upwardly

projecting ledge 17 which is adapted to enter the recess or rabbet 14 for preventing the entrance of rain and the like when the window sash is in closed position. A suitable weather strip 18 may also be employed for this purpose.

A screen 19 is adapted to be arranged beneath the window sash and by suitable mechanism, not shown, the screen may be manually raised and lowered thereby causing the raising and lowering of the window sash. When the window is in elevated position the screen will occupy the space between the lower portion of the window sash and the lower portion of the window frame or casing thus preventing the entrance of cinders and the like into the car, as is usual in such constructions.

Since the screen raising and lowering mechanism constitutes no part of the present invention it is not thought necessary to show and describe the same.

The screen 19 comprises a window supporting frame 20 and a screen frame 22 detachably secured thereto whereby the screen frame may be removed if desired without removing the supporting frame. The supporting frame 20 may be arranged in any suitable form as in the form of a rectangle as shown in Fig. 2. This frame is provided with stops against which the screen frame 22 engages when the parts are assembled. As shown, the frame 20 is formed from angle iron arranged in the form of a rectangle with one of the flanges 20^a extending inwardly in the plane of the frame to form a stop. The lower portion of the frame 20 has an extension 21 which is provided with an angular slot 21^a, which cooperates with a suitable holding and operating means, not shown.

It is sometimes a convenience to be able to remove the screen frame without removing the supporting frame. In other words, it is desirable that the frames be so constructed that they may be readily separated. The following mechanism is provided whereby this may be accomplished. The screen frame 22 is so constructed that it will fit within the supporting frame 20 and means are provided whereby the parts when properly assembled are automatically locked in position. The frames are provided with interlocking connections at one side thereof and with a detachable locking connection at 110

the opposite side. In the form shown, the lower portion of the screen frame 22 is provided with a recess 24 which is adapted to engage a corresponding head or corrugation 25 extending inwardly from the bottom portion of the supporting frame. The upper portion of the frame 20 is provided with a recess 26 in which is adapted to engage one or more spring-pressed latch bolts 27, two being shown.

The latch bolts 27 are beveled as at 28 for engaging the slightly upwardly bent edge 29 of the top portion of the frame 20 to cause the bolts to be retracted when the parts are being assembled. The recess 26 is shaped to conform to the outer end of the bolts 27 whereby a shoulder 31 is formed for retaining the screen frame in position in the window supporting frame, against the stop or flange 20^a.

Any suitable means may be employed for resiliently pressing the bolts 27 outwardly. As shown, the bolts 27 are mounted on the ends of a spring 32, the intermediate portion of which is rigidly secured to the upper portion of the frame 22. Suitable means are provided in the upper portion of the frame through which the bolts 27 extend, as clearly shown in Fig. 4 of the drawing. Provision is made for depressing the bolts 27. The devices shown for this purpose comprise finger pieces 27^a secured to the outer ends of the spring 32. The free ends of the finger pieces 27^a may extend outward through slots 32^a formed in the frame 22 opposite each locking bolt.

The screen frame 22 is provided with a sheet of foraminous or reticulated material, such as the wire screen or screen member 34. This material is secured to the frame in any suitable manner. As shown, the edges of the screen member 34 are secured in a groove 35 in the side of the hollow sheet metal frame 22 by means of a resilient retaining member 36 engaging a return-bend in the edges of the wire screen, as is usual in such construction.

In securing the screen frame 22 within the window supporting frame 20, the lower portion of the frame 22 is placed in the frame 20 with the recess 24 in engagement with the head or corrugation 25 and the top of said frame is then swung to nested position within said frame 20 against the stops or flange 20^a. The beveled face of the latch 27 will engage the inclined portion 29 of the flange of the frame 20 and thereby automatically withdraw the said latch. When the parts are in position the spring 32 will force the latch 27 outwardly behind the keeper or shoulder 31 thereby automatically locking the frame 22 in the frame 20.

I claim as my invention:

1. In combination, a rigid supporting frame formed from a bar L-shaped in cross-section and having one flange extending inwardly in the plane of the frame and the other extending laterally thereof, a screen frame, interengaging means between said screen frame and the laterally extending flange, said means being integral with said frames respectively, and a latch member on the opposite side of the said frames from said means for detachably holding said frames in assembled relation, said inwardly extending flange serving as an abutment for said screen.

2. In combination, a rigid supporting frame formed from a bar L-shaped in cross-section and having one flange extending inwardly and the other extending laterally, the laterally extending flange on the lower portion of said frame being formed with a bead, an inner hollow metallic frame provided with a recess for receiving said bead, and a latch within said hollow frame at the upper end thereof for engaging a recess on the upper portion of said laterally extending flange, said inwardly extending flange forming an abutment for the outer surface of said inner frame.

3. In combination, an outer frame formed from a channel bar having one side thereof provided with a corrugation extending the full length thereof and its opposite side with a keeper, a hollow inner frame provided on one of its sides with a recess for engaging said corrugation, a flat spring secured to said hollow frame and within the same on the side opposite said recess, and a latching bolt secured to the free end of said spring and extending through an opening in said frame for engaging said keeper for retaining said frames in assembled relation.

4. In combination, an outer frame, an inner frame, an interlocking connection between said frames extending along the entire length of one side thereof, a keeper on one of said frames, a flat spring, means for securing an intermediate portion of said spring to the other of said frames, latching members carried by the free ends of said spring and adapted to engage said keeper.

WILLIAM C. SMITH.
